UNITED STATES PATENT OFFICE.

HUGH BROWN, OF BATTLE CREEK, MICHIGAN, ASSIGNOR TO THE GREENSTREET FOLDING BOX MACHINE COMPANY, OF INDIANAPOLIS, INDIANA, A CORPORATION OF ARIZONA.

BOX-BLANK MACHINE.

1,140,297.

Specification of Letters Patent. Patented May 18, 1915.

Application filed October 6, 1913. Serial No. 793,786.

To all whom it may concern:

Be it known that I, HUGH BROWN, a citizen of the United States, residing at Battle Creek, in the county of Calhoun and State of Michigan, have invented a new and useful Box-Blank Machine, of which the following is a specification.

The object of my invention is to produce a machine by means of which box blanks, comprising one or more series of coördinatable cleats and associated sheet material 10 may be assembled into a box blank.

The accompanying drawings illustrate my invention; Fig. 1 being a side elevation 15 of a machine embodying the same; Fig. 2 a horizontal section immediately above the work table on line 2—2 of Fig. 3; Fig. 3 a vertical section on line 3—3 of Fig. 2; Fig. 4 a fragmentary section through one 20 of the feed-chain-carrying shafts; Fig. 5 a diagram of a portion of the feed-chains and associated cleats; Fig. 6 a transverse fragmentary section of the feed-chains, associated cleat and sheet guides, and a cleat 25 and sheet; Fig. 7 a fragmentary section on line 7—7 of Fig. 2; and Fig. 8 a fragmentary section on line 8—8 of Fig. 1.

In the drawings, 10 indicates a main frame carrying an anvil bar 11, anvils 12, 30 stapling mechanism 13, a shaft 14, eccentricities 15, eccentric strap 16, and pitman 17 connecting the eccentric shafts 16 with the reciprocating portion 13' of the stapling mechanism. Leading to the anvils 12 are 35 cleat guides 21, 21 through which cleats 22 are delivered to the anvils and projected through the stapling plane.

Thus far the parts are of any desired 40 form and the drawing is intended to illustrate these parts merely in a typical manner as they are well known and commonly now commercially in use in machines for producing box blanks.

Flanking each cleat guide 21 is a runway 23 through which travel a plurality of feed-chains which are preferably arranged 45 in pairs 24—24, 25—25, 26—26, and 27—27, which pairs are connected by cross bars 24', 25', 26', and 27', respectively, the cross bars 50 25', 26', and 27', extending over the intermediate chains without interfering with the movement of the same, although no cross bar can pass beneath any other cross bar so as to alter the proper sequence of the 55 bars. The outer two chains 27—27 are con-

nected by two closely adjacent cross bars 27' which in effect become a single cross bar of sufficient width to produce the desired spacing between the last cleat of one blank and the first cleat of the succeeding blank 60 and may therefore be considered as a single cross bar.

In the present drawings, I have shown the several pairs of chains connected each with a single cross bar and in most instances 65 such an arrangement is preferable although it will be readily understood that each pair of chains may be provided with several cross bars so that there will be two or more series of the same. The cross bars 24', 25', 70 26', and 27' are carried by blocks 28 one of each pair of which carries an upwardly projecting sheet gage finger 29 which serves to properly space the sheet sections of the blank, and the cross bars are of such thickness 75 as to properly space the cleats in end-to-end relation, as clearly indicated in Figs. 2, 3, and 5. If a single feed-chain were used instead of a pair, the overhanging of the cleat-engaging bars would result in a buckling 80 of the feed-chains which is most readily avoided by the use of the feed-chains in pairs in the manner shown.

The feed-chains are carried through the 85 stapling plane and at the receiving end of the machine they are supported upon idlers 31. Beyond the stapling plane chains 24—24 are carried by gears 32 keyed to shaft 33; chains 25—25 are carried by gears 34, keyed to shaft 35; chains 26—26 are carried by gears 36, keyed to shaft 37; and chains 27—27 are carried by gears 38, keyed to shaft 39. The shafts 33, 35, 37, and 39 are parallel with each other and it will be 90 readily understood that it is not material 95 which shaft drives any particular pair of chains. Journaled upon each shaft 33, 35, 37, and 39, adjacent the gears which are keyed to it, are idler gears 41 which support the chains which are positively driven 100 by the other shafts so that each pair of chains is controlled in its movement by a single shaft.

Each shaft 33, 35, 37, and 39 is under the control of a step-by-step or intermittently 105 active driving mechanism 42, and a continuously active, conveniently friction, driving mechanism 43.

Each friction driving mechanism comprises a gear, or sprocket, 44 journaled on 110

the shaft, and flanking friction disks 45 which are keyed to the shaft, and the several gears 44 are connected for simultaneous movement by a chain 46. One of the gears 44 carries a gear 47 over which a chain 48 passes to a driving gear 49, said driving gear being journaled upon the main drive shaft 51 which is connected to shaft 14 by any suitable means, such, for instance, as the gears 52 and 53. Running over gear 49 is a chain 54 which may be carried over either one of a pair of gears 55, 56, keyed to a counter-shaft 57. Shaft 57 also carries a gear 58 which is connected by a chain 59 with a gear 61 journaled on the drive shaft 51 and provided with a clutch member 62 which may be engaged by a clutch member 63 splined upon the shaft 51 and controlled through link 64, lever 65, and link 66, by a foot lever 67. The arrangement is such that, by shifting chain 54 to the proper gear 55 or 56, the friction driven speed of the feed-chains may be varied. It should be understood that any yielding driving mechanism may be substituted for the friction driving mechanism shown.

The ratchet driving mechanism for each shaft 33, 35, 37, and 39 comprises a ratchet wheel 71, a pawl-carrying lever 72, and a pawl 73 engaging the ratchet, and the several pawl-carrying levers are so proportioned and connected by the links 74 that simultaneous reciprocation of the pawl-carrying levers will produce simultaneous and uniform advancement of the several shafts 33, 35, 37, and 39. In order to obtain this ratchet advancement of the several feed-chain-carrying shafts, I connect a lever 75 to a link 75', attached to one of the pawl levers 72, said lever 75 having a slot 76 which receives the fulcrum 77. The lever 75 is swung by means of a pitman 78 operated by an eccentric 78' on shaft 14 and this pitman may be connected at any one of a number of points to the lever 75, as shown in Fig. 1.

It is desirable at times to temporarily prevent the ratchet driven movement of the feed-chains and it is for that reason that the slot 76 is provided, a link 79 being pivoted to lever 75 and to an arm 80, carried by a rock shaft 81 provided with a hand lever 82, the arrangement being such that by shifting the lever 75 to the left (Fig. 1) its effect on the pawl levers may be so diminished as to produce no advancement of the ratchet wheels. It will be readily understood that any desired form of intermittently-active advancing means may be substituted for that which has been described.

The pawls 73 are conveniently formed to co-act with springs 73' in such manner that they may be held in active or inactive position so that, when in inactive position, the adjacent shaft may be freely turned by hand

in order to bring the cross bar of the feed-chains controlled by that shaft, into any desired position.

In operation, the rear cross bar 27' will be brought to a position just in advance 70 of the stapling plane and the proper cleat inserted in the cleat guide behind it. Bar 24' will then be brought up behind that cleat, a second cleat inserted behind bar 24'; bar 25' brought up behind the second cleat; 75 a third cleat inserted; bar 26' brought up behind the third cleat, and a fourth cleat inserted behind the bar 26'. Thereupon sheet material is laid upon the first cleat, the machine is started, and the staples driven in 80 the ordinary manner. In this condition of parts the friction driving mechanisms, which are being advanced at a speed exceeding the speed of the ratchet driving mechanisms, will be incapable of advancing any of the 85 chains whose cross bars lie behind cleats whose forward movement is materially resisted but the advancement of these feed-chains and the cleats and sheets will be due solely to the ratchet driving mechanisms and 90 will therefore be synchronous, positive and step-by-step in coordination with the stapling mechanism; but chain 27, whose cross bar lies in front of the foremost cleat, 95 will be free to be driven forwardly continuously at a somewhat high speed so as to be brought up behind the fourth cleat and serve to keep this fourth cleat up against the cross bar of chain 26. Shortly after the appearance of the cross bar 27' at the receiving end of the cleat guide the cleat-providing operative will place a cleat in the cleat guide behind the cross bar 27' and, as the blank material is fed through the machine and the rear end of the first cleat 100 passes beyond the gears on shaft 33, the cross bar 24 will be drawn out from the space between the first and second cleats, as clearly indicated in Fig. 3, whereupon the friction driving mechanism on shaft 33 will 110 serve to rapidly advance chain 24 and bring its cross bar 24' up behind the first cleat of the next blank. It will be seen from the above, that it is only necessary for the cleat-providing operative to place a proper cleat 115 in the cleat guide between the cross bars of each two feed chains, and that it is not necessary for him to pay any further attention to the cleats so placed. By this arrangement, the feed chains are acted upon by the 120 ratchet feeding mechanism to positively drive the blank material through the machine for the stapling action and the friction driving mechanism operates to rapidly advance the chains through their inactive 125 portions of necessary travel.

As is customary in machines of this type, one of the cleat guides 21 is adjustable laterally toward and from the other cleat guide and for this purpose I provide the usual 130

screw threaded adjusting shafts 90, 90 connected by a sprocket chain 91. Some of these screw threaded shafts engage suitable nuts 92 carried by the cleat guide, and 5 others engage nuts in a bracket or plate 93 which connects the several groups of sprocket wheels associated with the chains of that cleat guide. In order to permit this lateral movement of the groups of sprocket 10 wheels each of the shafts 33, 35, 37, and 39 has splined upon it a sleeve 94 upon which the appropriate sprocket wheels will be keyed and the remainder journaled, as indicated in the center of Fig. 4 and these sleeves 15 94 are journaled in the bracket 93 but connected so as to partake in its lateral movement.

I claim as my invention:—

1. The combination of material-guiding 20 means, means for operating upon the material, a plurality of independently movable material-feeding members traversing to the same extent the guiding means, and two driving mechanisms for each material-feeding member, one of said driving mechanisms operating through the feeding members to drive the material in the guiding means, and the other of said driving mechanisms operating to move the feeding member through a portion of its path of travel.
2. The combination of material-guiding means, means for operating on the material, a plurality of feed-chains each carrying a member traversing the material-guiding 35 means, and a plurality of driving couples, one couple for each feed-chain, one member of each driving couple comprising intermittently operating driving mechanism operating to drive its feed-chain and material engaged thereby intermittently through the guiding means, and the other member of each couple comprising yielding driving mechanism capable of driving its feed-chain when sufficiently unopposed.
3. In a box blank machine, the combination of stapling mechanism, a cleat guide leading thereto, and a plurality of feed chains each having a portion traversing the cleat guide, a plurality of driving couples 40 for the said feed-chains, each couple comprising driving mechanism operating upon its feed-chain to drive the same positively step-by-step, and the other member of each driving couple comprising yielding driving 45 means acting upon its feed-chain to advance

the same when sufficiently unopposed at an average speed greater than the speed of the step-by-step driving mechanism, and means for synchronizing two or more of the step-by-step driving means.

4. In a box blank machine, the combination of a stapling mechanism, a cleat guide leading thereto, a plurality of independently moving feed-chains each having a portion traversing the cleat guide to the same 65 extent, ratchet mechanism operating at times upon the feed-chains to positively advance the same step-by-step, and other yielding driving means operating upon the feed-chains to drive the same when sufficiently 70 unopposed at an average speed greater than that obtained by the step-by-step driving means.

5. In a box blank machine, the combination of stapling mechanism, cleat guides 75 leading thereto, a plurality of feed-chains each having a portion traversing the cleat guide, a plurality of driving shafts each supporting and controlling one of the feed-chains, ratchet driving mechanism operating upon each drive shaft to advance the same step-by-step, and friction driving means operating upon each drive shaft to advance the same when sufficiently unopposed at an average speed greater than the 80 speed of the ratchet mechanism.

6. In a box blank machine, the combination of stapling mechanism, a cleat guide leading thereto, a plurality of independent movable material-feeding members traversing the cleat guide, each arranged to drive material therethrough, and two driving mechanisms for each material-feeding member, one of said driving mechanisms operating through the feeding members to drive 95 the material at one speed, and the other of said driving mechanisms operating to drive the material at a greater speed when unopposed by preceding material under the control of the first mentioned driving mechanism.

In witness whereof, I have hereunto set my hand at Battle Creek, Michigan, this 3rd day of October, A. D. one thousand nine hundred and thirteen.

HUGH BROWN.
